UNITED STATES PATENT OFFICE.

JACOB GRUENEBAUM, OF NEW YORK, N. Y.

COVER FOR GAS-GLOBES.

SPECIFICATION forming part of Letters Patent No. 245,714, dated August 16, 1881.

Application filed May 6, 1881. (No model.)

To all whom it may concern:

Be it known that I, JACOB GRUENEBAUM, of the city, county, and State of New York, have invented certain new and useful Improvements in Covers for Gas-Globes, of which the following is a specification.

This invention has reference to an improved cover or cap for gas-globes, by which a more perfect combustion of the carbon particles in the gas is obtained, separate smoke-bells dispensed with, and the blackening of the ceiling and walls by the deposit of carbon entirely obviated.

The invention consists of a smoke cap or cover for gas-globes, which is constructed with a central depression at its top and an annular bulge around its sides, and provided with an outwardly and downwardly projecting base-rim adapted to fit loosely over the top rim of the globe, and with slots or openings arranged above the rim for the escape of the gases of combustion. This central depression tends to direct the currents outward, and, together with the symmetrical spherical bulge, tends to produce an upward central current and circumferential downward currents free from choking eddies, causing a uniform mingling of the gas and atmospheric air, thereby promoting a steady and complete combustion.

The accompanying drawing represents a side view of my improved cover for gas-globes, in which A represents a smoke cover or cap, which is preferably made of opaque glass, and of any suitable size and design. This cover is constructed with a central depression at its top, and with a symmetrical annular bulge, the upper side of which forms a continuous curve with line of said depression. The cover A is fitted by means of a bottom rim, a, to the top edge of the glass globe with which it is to be used, and is provided above the rim with a series of slots or openings, b, of circular, elongated, or other shape, which are arranged in the lower part of the cover, the arched top part being closed and provided with a central exterior button or handle device, d, which serves to take hold of the cover in placing it in position on the globe or removing it therefrom. When the cover is placed upon the globe the particles of carbon which heretofore have escaped unburned, so as to be deposited upon the smoke-bells or the ceiling and walls, are thoroughly burned at the inside of the globe, the gases of combustion being emitted through the slots b of the cover.

The smoke-cover can be used with any gas-globe of corresponding size, is readily removed for cleaning, produces a better and steadier light, and forms an ornamental attachment to the gas-globes. In show-windows it has the additional advantage of protecting the goods exhibited therein against the danger of being burned.

Having thus described my invention, I claim as new and desire to secure by Letters Patent—

A cover for gas-globes constructed with a closed top having a central depression, and with a symmetrical annular bulge the upper side of which forms a continuous curve with the line of said depression, said cover being provided with an outwardly and downwardly projecting recessed lip adapted to fit closely over the top of the globe, and with holes around its lower parts above said lip, substantially as described.

In testimony that I claim the foregoing as my invention I have signed my name, in presence of two witnesses, this 29th day of April, 1881.

JACOB GRUENEBAUM.
